UNITED STATES PATENT OFFICE

ALBERT NOEL, OF BARCELONA, SPAIN

DEVICE FOR APPLYING SUBCALIBER BARRELS TO REVOLVERS OF THE SOLID-FRAME SWING-OUT CYLINDER TYPE

Application filed January 26, 1932, Serial No. 588,901, and in Spain December 16, 1931.

The device of the present invention serves to reduce the caliber of revolvers of the solid-frame, swing-out-cylinder type, so that a large-caliber revolver may be used for firing 5 cartridges of smaller caliber.

Said device is represented, merely by way of example, in the accompanying drawing, in which Fig. 1 is a side view of the sub-caliber barrel; Fig. 2 is a perspective view of 10 a block that takes the place of the cylinder of the revolver; Fig. 3 is a representation of the same block, seen from the opposite side; Fig. 4 represents the device applied to a revolver, and Fig. 5 illustrates a variation.

15 The sub-caliber barrel 1 (Fig. 1) is a cylindrical rod bored, rifled and chambered for the reduced-caliber cartridge to be employed, the bore being represented by the number 2. This barrel has on the outside two cylindrical 20 collars, or bushings, 3 and 4 of such diameter as to enter exactly into the barrel of the revolver, as represented by the dotted lines in Fig. 4.

25 The piece that replaces the cylinder (Figs. 2 and 3) has the form of a block 6—7, the longer arm of which 7 intersects the shorter 6, forming a right angle at 8. The shorter arm 6 of the block has a bore 9 with inside screw thread, into which can be screwed the 30 threaded chamber-end 10 of the sub-caliber barrel (Fig. 1), when the block occupies the cylinder space of the revolver, the sub-caliber barrel having been previously passed through the revolver barrel from the muzzle 35 5. The threaded end 10 of the sub-caliber barrel (Fig. 1) is that which contains the chamber.

40 When the block of the device occupies the cylinder space of the revolver and is in position for firing, the center of the bore 9 coincides with the axis of the revolver barrel and the firing-pin-hole of same, if the cartridge for which the sub-caliber device is adapted is center-fire. If this cartridge is 45 rim-fire, the perforation 9 is somewhat lower, so that the firing-pin-point of the hammer will strike on the cartridge rim.

50 The shorter arm 6 of the block of the sub-caliber device has on its outside, or rear, surface a flat, cup-like projection 12 to engage

in the cylinder lock 13, if the revolver is of the Colt system; and for revolvers of the Smith & Wesson system it has a projecting pin with rounded point (Fig. 5, Num. 14), which can be depressed, since its base 17 55 rests upon a spiral spring 15 and is held in place by a screwed plug 16, through which it passes. The pin engages in the cylinder lock of Smith & Wesson and other revolvers of similar construction.

These projections 12 and 14 on the rear surface of the block to engage in the cylinder lock of the revolver serve to hold the block 6—7 firmly in place, while the sub-caliber barrel (Fig. 1), which is screwed into it, 60 passes through the bore of the revolver.

When the device is in the locked, or firing, position the notch 18 on the long arm of the block 6—7 engages with the forward inside surface of the cylinder space of the revolver 70 (opposite the recoil plate) and this holds the rear projection 12 or 14 firmly in the cylinder lock 13, so that block and sub-caliber barrel are kept rigid.

If the cylinder lock 13 is opened and the 75 long arm of the block 7 is pushed from the right side of the revolver towards the left, the block swings out; the notch 18 disengages from the frame, and the whole device can be moved a short distance forward, the 80 sub-caliber barrel sliding through the bore of the revolver. This leaves the rear portion of the device free for knocking out the fired cartridge with a metal rod passed through the barrel and for inserting a new 85 cartridge into the chamber 10.

Fig. 3 shows how the rear sight 19 for reduced caliber practice can be attached to the block 6 by means of a set screw 20 without need of removing the sight from the block or changing the adjustment of the sight when the device itself is removed from the revolver. The set screw 20 passes through a vertical slot 21 which allows the base of the sight to be 90 moved upward and downward. This same movement may be obtained by means of a 95 ratchet.

I claim:—

1. A sub-caliber barrel attachment for revolvers of the solid-frame, swing-out-cylin- 100

- der type, comprising a sub-caliber barrel slidably fitting the bore of the revolver barrel and adapted for introduction therein from the muzzle end, and a swinging retaining block fixedly to engage with the rear end of the sub-caliber barrel and to occupy the revolver cylinder space in the absence of the cylinder.
2. A sub-caliber barrel attachment for revolvers of the solid-frame, swing-out-cylinder type, comprising a sub-caliber barrel slidably fitting the bore of the revolver barrel and adapted for introduction therein from the muzzle end, said sub-caliber barrel being chambered at the rear end, and a swinging retaining block fixedly to engage with the rear end of the sub-caliber barrel and to occupy the revolver cylinder space in the absence of the cylinder.
3. A sub-caliber barrel attachment for revolvers of the solid-frame, swing-out-cylinder type, comprising a sub-caliber barrel slidably fitting the bore of the revolver barrel and adapted for introduction therein from the muzzle end, the rear end of the said sub-caliber barrel being screw-threaded on the exterior and chambered at the interior, and a retaining block to occupy the revolver cylinder space in the absence of the cylinder, the retaining block being provided with a screw-threaded bore to receive the screw-threaded end of the sub-caliber barrel.
4. A sub-caliber barrel attachment for revolvers of the solid-frame, swing-out-cylinder type, comprising a sub-caliber barrel slidably fitting the bore of the revolver barrel and adapted for introduction therein from the muzzle end and to extend rearwardly beyond the end of the revolver barrel, and a retaining block fixedly to engage the rear end of the sub-caliber barrel and to occupy the revolver cylinder space in the absence of the cylinder, said retaining block having a laterally disposed front extension adapted to lie against the revolver frame, and means at the rear to engage the revolver cylinder lock in order that on release of the cylinder lock the retaining block may be swung outward about the axis of the sub-caliber barrel to clear the revolver frame and the sub-caliber barrel may be moved forwardly in the revolver barrel to expose the chamber.
5. A sub-caliber barrel attachment for revolvers of the solid-frame, swing-out-cylinder type, comprising a sub-caliber barrel slidably fitting the bore of the revolver barrel and adapted for introduction therein from the muzzle end, and a swinging retaining block fixedly to engage with the rear end of the sub-caliber barrel and to occupy the revolver cylinder space in the absence of the cylinder, said retaining block carrying a cup-shaped projection to engage the cylinder lock of the revolver.
6. A sub-caliber barrel attachment for revolvers of the solid-frame, swing-out-cylinder type, comprising a sub-caliber barrel slidably fitting the bore of the revolver barrel and adapted for introduction therein from the muzzle end, and a swinging retaining block fixedly to engage with the rear end of the sub-caliber barrel and to occupy the revolver cylinder space in the absence of the cylinder, said retaining block carrying means to engage the revolver cylinder lock comprising an axially movable pin adapted to project to a limited extent from the face of the said retaining block and a spring urging the said pin to its outermost position.
7. A sub-caliber barrel attachment for revolvers of the solid-frame, swing-out-cylinder type, comprising a sub-caliber barrel slidably fitting the bore of the revolver barrel and adapted for introduction therein from the muzzle end, and a swinging retaining block fixedly to engage with the rear end of the sub-caliber barrel and to occupy the revolver cylinder space in the absence of the cylinder, said retaining block carrying an adjustable rear sight which is removable from the revolver with the said retaining block.
- ALBERT NOEL.
